BEST AVAILABE CAPT.

UNITED STATES PATENT OFFICE.

JOHN NICHOLSON, OF FRACKVILLE, PENNSYLVANIA.

CARBON PENCIL OF ELECTRIC-ARC LIGHTS.

No. 901,993.

Specification of Letters Patent.

Patented Oct. 27, 1908.

Application filed April 20, 1908. Serial No. 428,009.

To all whom it may concern:

Be it known that I, JOHN NICHOLSON, a citizen of the United States, residing at Frackville, in the county of Schuylkill and State of Pennsylvania, have invented certain new and useful Improvements in Carbon Pencils of Electric-Arc Lights, of which the following is a specification.

My invention relates to carbon pencils of electric arc lights and particularly to the lower carbon of lower electrode.

My invention relates more specifically to the cored lower electrode of the so called "luminous" arc light.

15 My invention will be more readily understood by reference to the accompanying drawing which is a longitudinal sectional view of an electrode embodying my invention in its preferred form.

20 Referring now to the drawings, 1 indicates a carbon pencil which is designed as the lower electrode of an arc light. This is centrally cored as at 2, and filled with a suitable mixture as at 3, which is composed of 25 any of the substances now used for this purpose.

The end is closed or covered by a cap 4. This is formed of a disk of thin sheet iron and is held in place by a metal strip 5, which 30 is secured to the center of the underface of the disk and extends substantially centrally through the core 3. The substance of which the core is composed is a non-conductor or at the best a poor conductor. For obvious reasons I do not care to pass the current di-

rectly through the core or to establish a circuit through the member 5, hence the strip 5 terminates some distance from the socket end of the electrode or pencil. The member 5, is formed preferably of iron wire, Number 40 14 gage being found by experiment to be the most suited for the purpose. The pencil is completed by a cylindrical jacket 6, incasing the carbon 1, and formed of thin sheet iron.

45 Having thus described my invention what I claim as new and desire to secure by Letters Patent is:—

1. An electrode for an arc light comprising a cored carbon pencil having a metal cap 50 and a metal strip secured to said cap and extending substantially centrally through the core, substantially as described.

2. An electrode for an arc light comprising a cored carbon pencil having a metal cap 55 and a metal strip secured to said cap and extending centrally through said core and terminating at a distance from the socket end, substantially as described.

3. An electrode for an arc light comprising a cored carbon pencil having a metal cap 60 and a metal jacket, substantially as described.

In testimony whereof I have signed my name to this specification in the presence of 65 two subscribing witnesses.

JOHN NICHOLSON.
